CLARENCE W. HAZELETT, OF LAKEWOOD, OHIO, ASSIGNOR, BY MESNE ASSIGNMENTS,
TO NATIONAL CARBON COMPANY, INC., A CORPORATION OF NEW YORK.

CASTING APPARATUS.

1,318,380.

Specification of Letters Patent. Patented Oct. 14, 1919.

Application filed April 30, 1917. Serial No. 165,358.

To all whom it may concern:

Be it known that I, CLARENCE W. HAZELETT, a citizen of the United States, residing at Lakewood, in the county of Cuyahoga and State of Ohio, have invented a certain new and useful Improvement in Casting Apparatus, of which the following is a full, clear, and exact description.

This invention relates to apparatus for casting storage battery parts. While the invention is described and illustrated as applied to making a certain type of lead casting, it will be evident to one skilled in the art that by suitable variations the apparatus may be adapted for making other forms of castings either from lead or other materials.

In molding small lead castings of the type shown for storage battery purposes, an apparatus is usually used comprising two small die blocks which the molder fits together manually. Core pins or other accessories are then fitted in the mold to provide means for producing the desired shape of casting. After the lead is poured in the gate the core pins are removed, the blocks separated and the casting removed from the side of the mold in which it clings. This method of operation requires considerable handling of the component parts of the mold and is therefore slow and tedious. Inasmuch as the mold parts become hot after casting a few pieces they are troublesome to handle. It is furthermore generally difficult to remove the article from the mold because it sticks in one side or the other and requires hammering the mold to loosen it.

The object of my invention is to eliminate the previously mentioned disadvantages and to facilitate molding of such parts.

In the drawings:—

Figure 1 is a plan view of the apparatus with the mold closed.

Fig. 2 is a plan view with the mold open.

Fig. 3 is a side view with the mold opened.

Fig. 4 is a cross section on the broken line A—A of Fig. 1.

Fig. 5 is a cross section on the line B—B of Fig. 1.

Fig. 6 is a cross section of a modification

with the mold open and the article in position.

Fig. 7 is a partial horizontal cross section taken on the line C—C of Fig. 6.

Fig. 8 is a cross section similar to Fig. 6 showing a modification.

Two cylinders 1, 1, placed in alinement are closed at corresponding ends by angular members having one face 2 bolted to the cylinder end and the other face 3 bolted or otherwise fastened to a table or support of any suitable nature. The adjacent ends of the cylinders are similarly closed by angular members 4 having legs 5 resting on the table. The end closing members 4 are rigidly joined by means of a heavy smooth metal plate 6 fastened to each of the legs 5. In the center of plate 6 an opening 7 is cut which is preferably circular. Piston rods 8 connected with the piston heads 9 of each cylinder 1 pass through the ends 2 and are fastened to the center of plates 10. Rods 11 and 12 pass through holes in the ends of each of the plates 10 and are rigidly fastened therein by nuts 13 and 14 placed on either side of the plates. The rods 11 and 12 extend on either side adjacent the cylinders 1 and have nuts 15 and 16 fitted on the threaded ends 17. Air pressure is applied through pipe 18 to move the pistons in opposite directions against the action of springs 19 placed in the cylinder. When the air pressure is released the springs cause the pistons to approach and close the mold. It will be evident that instead of air pressure and spring pressure any other means could be used to operate the pistons.

The portion of the apparatus just described will be permanently fastened to an operating table and will receive various movable portions for casting different articles. These parts will be fastened to the operating elements by means of the four pairs of nuts 15 and 16 fitted on the ends 17 of the rods 11 and 12.

The removable part of the apparatus consists of two bars 20 and 21 having slots 22 (Fig. 4) which receive rods 11 and 12 to which the bars are fastened by means of nuts 15 and 16. The two halves of the

- mold 23 and 24 are fastened by means of bolts 25 to the bars 20 and 21 respectively. The lower surfaces of the molds slide on the flat surface of plate 6 and when the inner surfaces having the outline of the article therein are pressed together a perfect joint is formed at the parting line 26. The gate 27 is cut in the surface of one or both sides of the mold adjacent the parting line.
- 10 The mold parts 23 and 24 have suitable openings 28, 29 of the same diameter or shape as core pins 30, 31, which fit therein and project into the mold forming cavities to provide the desired configuration. The 15 core pins are adapted to be fitted on threaded members 32, 33. Each of these has an enlarged portion 34 having a slot therein in which are placed two links 35, 36 which are pivotally connected together by a pin 37.
- 20 The other ends of links 35 and 36 are connected to bars 20 and 21 by pins 38 and 39. To center the two cores 30 and 31 one may be pointed and the other have a depression 40.
- 25 A centering member 41 preferably cylindrical in shape, has a projection 42 closely fitting in the hole 7 of the plate 6 which serves to hold the member 41 therein. The portion 41 rests on the surface of the plate 30 and is of the same cross section as the openings in the bottom of the mold parts. By cutting away the edge of the centering member adjacent the plate 6, and the edge of the die 24 adjacent the plate 6 at the parting line, spaces 50 and 51 (Fig. 4) are provided 35 in which dust may accumulate without preventing the dies from closing. Instead of cutting away the edge of the centering member, the corresponding edges of the dies may be removed to provide spaces 52 for dust as shown in Fig. 8.

In the modification shown in Figs. 1 to 5, the centering member is provided with an opening 43 for receiving a screw 44 which 45 will be cast in the article. The modification of Figs. 6 and 7 differs from that of Figs. 1 to 5, in having an opening 45 in the centering member 41' which serves for receiving a portion of the casting rather than a screw 50 which is cast in the molded article.

In Fig. 8 a modification is shown in which the centering member 48 is held in the plate 6 by a nut 46 fitted on a projection 47 passing through the plate 6. The centering projection 48 projects into the mold forming cavity a sufficient distance to produce an additional hole in the casting. The lower part of the centering member is a counterpart of the opening formed in the bottom of the mold when the two parts are pressed together.

In utilizing the apparatus it will be operated in the following manner. If it is desired to cast the article shown in cross section in Fig. 5, the molding parts just de-

scribed will be fastened to the rods 11 and 12 attached to the pistons 9 in the manner described. The two halves 23, 24 of the mold are then separated by simultaneously applying air pressure to the pistons 9 by 70 opening a single valve (not shown).

The centering member shown in Fig. 5 is then inserted in the plate 6 and a screw placed in the hole 43. The mold is then closed by the force of the springs when the 75 air pressure is exhausted. When the mold parts are thus closed the centering member 41 coöperating with its counterpart in the bottom of the mold serves to accurately line up the configurations in the two halves of 80 the mold. The notches 50 and 51 in the dies and centering member prevent dust from collecting at the parting line and preventing the mold from closing. The movement which closes the mold also pushes the core 85 pins 30 and 31 inward until they come into contact. Molten lead is then poured into the gate to fill the mold cavity, or forced in by any well known pressure casting method. When the two halves of the mold are separated by again applying air pressure, the cores will be simultaneously withdrawn and the article will be retained upright on the centering member 41. The pin 44 cast in the article and projecting down into the 95 hole 43, as well as the core pins, prevent the article from sticking in either side of the die. The removal from the centering member is then carried out without difficulty as there is scarcely any sticking tendency. The 100 use of the centering member thus prevents sticking in either side. The centering member remains in place for molding additional articles. It will be evident that in casting the article shown in Fig. 5 which has a 105 double taper, the cores will be readily withdrawn.

The mechanism described may provide a very considerable force for pulling the core pins and separating the dies so that very 110 little draft is required.

The modifications shown in Figs. 6 and 8, further illustrate an important feature of my invention, namely a centering member serving simultaneously for centering the 115 mold parts and retaining the casting when the mold parts are separated, whereby it does not stick in either side. In Fig. 6 this is done by casting a portion of the article in the centering member so that the part 120 projecting therein serves the same purpose as the pin 44 fitted in the opening 43 of the previously described modification. The sticking tendency in this case is also so slight that the loose centering member is not lifted 125 out of the hole 7 in plate 6.

In Fig. 8 the centering member has an upper portion which serves the purpose of a core as well as the centering functions previously described. To prevent the centering 130

member from being lifted from the plate when the article is drawn therefrom, a nut 46 is threaded on projection 47.

While I have illustrated several modifications, other modifications embodying my invention may be used for making various articles but after the foregoing disclosures such will be evident to one skilled in the art. The invention is obviously not limited to 10 casting a double taper post as it can be used in casting other types of posts.

Having described my invention, what I claim is:—

1. In apparatus for casting articles, a plate, a mold divided into two parts each having a cavity, said cavities forming two openings when the mold is closed, one opening being adjacent said plate and the other on one side, a projection fitted to the plate having a depression for receiving a portion of the article, a core pin adapted to be fitted in the side opening, and means for separating the mold parts and withdrawing the core pin.

2. In apparatus for casting articles, a plate, a mold divided into two parts each having a cavity, said cavities forming two openings when the mold is closed, one opening being adjacent said plate and the other on one side, a projection fitted to the plate adapted to register with the first mentioned opening, said projection having a depression for receiving a portion of the article, a core pin adapted to be fitted in the side opening, and means for separating the mold parts and withdrawing the core pin.

3. In apparatus for casting articles, a plate, a mold divided into two parts each having a cavity, said cavities forming three openings when the mold is closed, one opening being adjacent said plate and the other two on opposite sides, a projection fitted to the plate adapted to register with the first mentioned opening, said projection having a depression for receiving a portion of the article, a pair of core pins adapted to be fitted in the side openings, and means for simultaneously separating the mold parts and withdrawing the core pins.

4. In apparatus for casting articles, a plate, a mold divided into two parts, each having a cavity, said cavities providing three openings when the mold is closed, one opening being adjacent said plate and the other two on opposite sides, a movable piston connected to each of the mold parts, a projection fitted to the plate adapted to register with the first mentioned opening, said projection having a depression for receiving a portion of the article, a pair of core pins adapted to be fitted in the side openings, means for simultaneously applying pressure to the pistons to separate the mold parts, and means for withdrawing the core pins.

5. In apparatus for casting articles, a

plate, a mold divided into two parts each having a cavity, said cavities forming two openings when the mold is closed, one opening being adjacent said plate and the other on one side, an arm extending from each mold part, a piston connected to each mold part, a projection fitted to the plate adapted to register with the first mentioned opening, said projection having a depression for receiving a portion of the article, a core pin adapted to be fitted in the side opening, a pair of links connecting the core pin to the extending arms, and means for applying pressure to the pistons to separate the mold parts and simultaneously withdraw the core pins.

6. In apparatus for casting articles, a plate, a mold divided into two parts each having a cavity, said cavities forming three openings when the mold is closed, one opening being adjacent said plate and the other two on opposite sides, a projection fitted to the plate adapted to register with the first mentioned opening, said projection having a depression for receiving a portion of the article, a pair of arms extending on opposite sides of each mold part, a piston connected to each mold part, a pair of core pins adapted to be fitted in the side openings, a pair of links connecting a core pin to an arm of each mold part, a second pair of links connecting the other core pin to the other arm of each mold part, and means for applying pressure to each of the pistons to simultaneously separate the mold parts and withdraw the core pins.

7. In apparatus for casting articles, a mold divided into two part each having a cavity, said cavities forming an opening in one side of the combined parts when the mold is closed, a core pin adapted to be fitted in said opening, an arm extending from each mold part, a pair of links connecting the core pin to the arms of the mold parts, and means for separating the mold parts whereby the core is simultaneously withdrawn from the opening.

8. In apparatus for casting articles, a mold divided into two parts each having a cavity, said cavities forming openings on two opposite sides when the mold is closed, a pair of arms extending on opposite sides of each mold part, a pair of core pins adapted to be fitted in the side openings, a pair of links connecting a core pin to an arm of each mold part, a second pair of links connecting the other core pin to the other arms of each mold part, and means for separating the mold parts whereby the cores are simultaneously withdrawn from the openings.

9. In apparatus for casting articles, a mold divided into two parts each having a cavity, said cavities forming openings on opposite sides when the mold is closed, a

pair of arms extending on opposite sides of each mold part, a piston connected to each mold part, a pair of core pins adapted to be fitted in the side openings, a pair of links connecting a core pin to an arm of each mold part, a second pair of links connecting the other core pin to the other arm of each

mold part, and means for applying pressure to each of the pistons to simultaneously separate the mold parts and withdraw the core pins.

In testimony whereof I hereunto affix my signature:

C. W. HAZELETT.
